UNITED STATES PATENT OFFICE.

GEORGE M. CLASS, OF MADISON, WISCONSIN, ASSIGNOR TO GISHOLT MACHINE COMPANY, OF MADISON, WISCONSIN, A CORPORATION OF WISCONSIN.

TOOL POST.

Application filed August 18, 1926. Serial No. 129,885.

This invention relates to tool posts for lathes and other machine tools employing tool posts, and has reference more particularly to tool posts of the turret type capable of holding a plurality of tools and of being indexed to bring the latter successively into operative relation to the work.

The main object of the present invention is to provide a very simple, inexpensive and efficient tool post, in which, by swinging a handle lever through an angle slightly greater than the indexing angle, the tool post will be indexed and clamped. Another object is to provide an improved and simplified mechanism for unlocking the tool holder when the latter is to be indexed.

In the accompanying drawings I have illustrated the invention as embodied in a square turret tool post designed to be indexed through an angle of ninety degrees but it will be understood, of course, that the invention is equally applicable to tool posts designed to be indexed through greater or less angles.

Referring to the drawings—

Fig. 1 is a top plan view;

Fig. 2 is a vertical section taken on the line 2—2 of Fig. 1;

Fig. 3 is a horizontal section taken on the line 3—3 of Fig. 2;

Fig. 4 is an elevation; and

Figs. 5 and 6 are detail perspective views of a rotatable sleeve through which the retracting movements of the locking bolt are effected.

Referring to the drawings, 10 designates the base of the tool post that is held down on the cross-slide 11 (Fig. 4) by bolts 12 and nuts 13, which latter are adjustable in the usual T-slots 14 of the cross-slide. The upper portion 10' of the base 10 is circular, and mounted thereon is the tool holder body 15 equipped with the usual lateral flange 15' carrying screws 16 by which the tools are clamped on the wedges 17. Extending coaxially through the base 10 and body 15 is a stud 18 that is formed with a threaded lower end 19, a threaded upper end 20, and an enlarged central portion 21. On the threaded lower end 19 of the stud is a nut 22 adapted to move into clamping and release engagement with the bottom of the

base, as hereinafter described, and pinned to the upper threaded end 20 of the stud is an operating arm 23. The tool holder body 15 is further centered and revolvably guided on the base by a circular flange 24 on its lower end embracing the circular upper portion 10' of the base.

Referring to Fig. 2, mounted in the base 10 is a bushing 25 in which is slidably mounted a locking bolt 26 chambered in its lower portion to house a thrust spring 27 by which it is normally pressed upwardly into one of a series of sockets 26' formed at 65 spaced intervals in the bottom of the tool holder 15. The spring 27 is footed on a pin 28 that is mounted in a lug 22' formed as a lateral extension of the clamping nut 22. The nut 22 is also formed with a vertical 70 slot 29 that accommodates a lateral projection or foot 30 formed on the locking bolt 26.

Encircling the stud 18 below its central enlarged portion 21 is a rotatable sleeve 31, shown in isometric detail in Figs. 5 and 6. 75 Said sleeve has a circumferential bearing in the bore of the base 10 and is confined against any substantial end play downwardly by the nut 22 and upwardly by co-operating annular shoulders 32 and 33 on the sleeve 80 31 and its bearing in the base 10, respectively. The lower end of the sleeve 31 is formed to provide a plurality of spaced notches 34 each formed with an abrupt substantially vertical wall 35, and an inclined 85 wall 36 that functions as a cam, when the sleeve is turned, to depress and retract the locking bolt 26 through its foot 30. Flat portions 37 extending between the vertical wall 35 of one notch and the cam wall 36 of 90 the next notch serve, through engagement with the foot of the locking bolt to hold the latter retracted during the indexing movement of the tool holder.

The sleeve 31 is turned in one direction 95 only; and for this purpose the upper end of the sleeve is formed with a plurality of ratchet teeth 38, these teeth co-operating with a pawl 39 that is mounted to slide vertically in a hole in the enlarged portion 100 21 of the stud 18. The pawl 39 is pressed downwardly into co-operating engagement with the ratchet by a spring 40. Assuming that the lower end of the pawl 39 is in con-

tact with one of the ratchet teeth 38, manifestly a turning movement of the arm 23 in a counterclockwise direction will cause the sleeve 31 to turn in the same direction, and 5 the engagement of one of the cams 36 on its lower end with the foot of the locking bolt will retract the latter and bring said foot into sliding engagement with the holding face 37 until said foot slides off the latter 10 into the next notch, this occurring at the completion of each indexing movement to permit the locking bolt to re-engage with the next socket in the tool holder.

Similar pawl and ratchet mechanism is 15 preferably employed to transmit the turning movement of the stud 18 to the tool holder; this last-named pawl and ratchet mechanism being timed to operate in immediate succession to the operation of the 20 bolt retracting mechanism, so that the tool holder may be unlocked, then indexed to a new position, and automatically relocked by a single continuous movement in one direction of the operating arm or lever 23. The 25 mechanism for turning the tool holder is best shown in Fig. 3, wherein it will be seen that the bore of the tool holder which forms in part a bearing for the enlarged portion 21 of the stud is formed with a plurality of 30 spaced ratchet teeth 41, which, for greater durability are preferably formed in hardened steel pins 42 non-rotatably fitted into seats in the tool holder body. Co-operating with the ratchet teeth 41 is a pawl 43 that 35 is slidable horizontally in a transverse hole in the stud section 21 and urged outwardly by a spring 44. The operation has been for the most part set forth in the foregoing description of the structure, but may be briefly 40 outlined as follows.

The bolt retracting cams 36 being, in the instance shown, about thirty degrees long the first thirty degrees of swinging movement of the arm 23 in a counterclockwise direction effects the retraction of the bolt. At 45 that point the pawl 43 comes into engagement with one of the ratchet teeth 41; and the continued swing of the arm 23 in the same direction through another ninety degrees effects the indexing of the tool holder 50 to a new position, at which point the foot of the locking bolt drops into another notch 34 of the cam sleeve and the bolt simultaneously engages with the next socket of the 55 tool holder and thus locking the latter in its newly indexed position. When the operating arm is reversed through the same arc as its forward movement, the nut 22 is drawn up tight against the base 10 clamping the 60 whole post rigidly together, and the pawls 39 and 43 snap back into position again as the operating arm is reversed, ready to effect the next unlocking and indexing movement of the post. If more than ninety degrees is 65 to be indexed at one time, by moving the op-

erating arm sufficiently to withdraw the locking bolt, and then moving the tool holder the rest of the way by hand, and then reversing the arm the tool post may be clamped in any position.

I claim—

1. In a tool post, the combination of a base, an upwardly spring-pressed locking bolt in said base formed with a lateral projection, a tool holder rotatable on said base having sockets in its under side to interlock with the upper end of said bolt, a rotatable stud extending centrally through said base and tool holder, said stud formed with an enlarged intermediate portion, an operating arm fast on the upper end of said stud, a rotatable sleeve encircling said stud beneath said enlarged portion, said sleeve formed on its lower end with cams cooperating with said projection to retract said bolt and on its upper end with ratchet teeth, a downwardly spring-pressed pawl slidably mounted in said enlarged portion cooperating with said ratchet teeth to turn said sleeve, and cooperating means carried by said enlarged portion and the tool holder operative to index the latter by a continued movement of said arm in the same direction after said bolt has been retracted.

2. In a tool post, the combination of a base, an upwardly spring-pressed locking bolt in said base formed with a lateral projection, a tool holder rotatable on said base having sockets in its under side to interlock with the upper end of said bolt and internal 100 ratchet teeth, a rotatable stud extending centrally through said base and tool holder, said stud formed with an enlarged intermediate portion embraced by the upper portion of said base and the lower portion of 105 said tool holder, an operating arm fast on the upper end of said stud, a rotatable sleeve encircling said stud beneath said enlarged portion, said sleeve formed on its lower end with cams cooperating with said projection 110 to retract said bolt, pawl and ratchet means carried by said enlarged portion and the upper end of said sleeve for turning the latter, and a horizontally slidable spring-pressed pawl mounted in said enlarged portion 115 cooperating with the internal ratchet teeth of said tool holder to index the latter by a continued movement of said arm in the same direction after said bolt has been retracted.

3. In a tool post, the combination of a base, an upwardly spring-pressed locking bolt eccentrically mounted in said base and formed on its lower end with a lateral projection, a tool holder rotatable on said base having sockets in its under side to interlock 125 with the upper end of said bolt, a rotatable stud extending centrally through said base and tool holder, an operating arm fast on the upper end of said stud, a nut on the lower end of said stud adapted for clamp- 130

ing engagement with said base, cooperating means carried by said locking bolt and nut for locking the latter against turning, a rotatable sleeve encircling said stud formed on its lower end with cams cooperating with said projection to retract said bolt, pawl and ratchet means carried by said stud and sleeve for turning the latter, and pawl and ratchet means carried by said stud and tool holder operative to index the latter by a continued movement of said arm in the same direction after said bolt has been retracted. 10
